UNITED STATES PATENT OFFICE.

RICHARD T. CHILES, OF PORTLAND, MAINE.

SNOWPLOW.

Application filed June 19, 1924. Serial No. 720,922.

To all whom it may concern:

Be it known that I, RICHARD T. CHILES, a citizen of the United States, residing at 57 Sherman St., Portland, in the county of 5 Cumberland and State of Maine, have invented certain new and useful Improvements in Snowplows, of which the following is a specification.

The present invention relates to shovels 10 or plows to be used in removing snow from sidewalks, paths, roads and the like.

In regions where the snowfall is heavy the removing of snow from paths, sidewalks and roadways requires a great deal of 15 time, labor, and expense. It is therefore of importance to devise means for reducing these factors as much as possible. I am aware that snow plows have been used on the railroads and that these plows employ 20 certain of the mechanism used in my device as for instance the rotary shovel. I am also aware that the shovels used by the railroads are power driven and are adapted to throw the snow to one side of the track on which 25 the machine is running. None of these machines however are constructed for an easy manipulation in and adaptation to a path, a sidewalk, or a roadway having sharp turns and an irregular course, neither are they so 30 constructed as to be readily adapted to light as well as to deep snow. Further, these devices are either manipulated with a great expenditure of labor or involve complicated and expensive mechanism.

Objects of the present invention are to 35 provide a snow plow that can be operated with a minimum of labor; that will be mobile; easily and simply adaptable to various conditions of a roadway or sidewalk 40 and that will be simple of construction, and economical of manufacture.

Another object is to relieve the operator as 45 much as possible of the weight of the machine in the operation thereof and to arrange the operating mechanism for easy and convenient manipulation.

In carrying out the above objects, I provide a frame with a casing mounted on one end thereof having a rotary shovel and a feed wheel journaled therein and at the 50 other end handles such as are provided on

trucks and wheelbarrows. The frame also has motive means for driving the shovel and feed wheel mounted thereon and the frame so equipped is mounted on means to afford rotative locomotion, preferably wheels attached intermediate its ends in position so that their common axis will be approximately under but preferably a little forward of the center of gravity of the machine. 60

Another object of the invention is to provide power driven means which may be engaged with the wheels on which the frame is mounted for driving them or disengaged therefrom, at the will of the operator. 65

Another object of the invention is simplicity of construction and of operation and economy in manufacture.

Another object is the arrangement of the exhaust pipe leading from the engine so as 70 to materially reduce the noise of discharge.

Another object is to so arrange the bearings on the main shafts carrying the shovels and feed wheel as to maintain the said shovel and feed wheel against displacement from 75 their position in their casings.

A further object is to adapt the machine for operation in a small area and in places where there is a necessity of making frequent and short turns. 80

Various other objects, advantages and features of novelty will appear from the following specification taken with the accompanying drawings and will be pointed out in the appended claims. 85

In the drawings:

Fig. 1 is a side elevation of the snow plow.

Fig. 2 is a plan view thereof, with the engine omitted.

Fig. 3 is a side elevation similar to Fig. 1, 90 showing the machine tilted to position for removing snow close to the ground.

Fig. 4 is a longitudinal section through the shovel and feed wheel casings, taken on the line 4—4, Fig. 2, showing the relation 95 of parts therein, said view being on an enlarged scale relative to Figs. 1, 2, and 3.

Fig. 5 is a cross section of the casings taken at right angles to the section shown in Fig. 4, and on the line 5—5, Fig. 4. 100

Fig. 6 is a view on a still larger scale than Fig. 4, showing in longitudinal section the

details of the clutch for throwing the locomotive wheels of the machine into driving connection with the power of the machine.

Fig. 7 is a detail end view of the clutch 5 showing the cam arrangement for operating the clutch.

Fig. 8 is a detail view showing the connection of the right hand traction wheel with the traction shaft, whereby it is adapted to rotate with or rotate relative to the shaft at the will of the operator.

I will now describe my invention in detail referring to the parts on the drawings by reference numerals, the same numerals 15 designating the same parts in all views.

In the present embodiment of the machine constituting my invention, 10 designates a frame consisting of a pair of beams 11 arranged in parallelism with each other and 20 connected together near one end of the frame by a rod 12, the other ends of the beams being connected to a shovel casing 13, to which a feed wheel casing 14 is attached. The ends of the beams adjacent the rod are formed 25 for convenience of manipulation of the machine into handles 15.

Within the shovel casing are a plurality of shovels 16 which are arranged in spaced relation to each other and extend radially 30 from a main shaft 17 which latter extends axially of the casing. The shovels comprise radial strips 18 connected at their outer ends by other strips 19 constituting the shovel blades. On the outer end of the shaft and in 35 front of the shovel blades, is a feed wheel 20 comprising blades 21 which extends radially from a suitable hub 22 keyed to the shaft 17. The blades of the feed wheels are preferably turned at an angle to the plane 40 passing through the hub at right angles to its axis after the manner of propeller blades. On the forward end of the feed wheel casing is secured a scoop 23 adapted for easy projection into the snow and having the upper 45 edges of its sides sloping rearwardly and upwardly toward the casing. Tangentially arranged relative to the shovel casing and communicating therewith is a discharge chute 24 opening at one side of the machine 50 so as to throw the snow to one side of the path or walk being cleaned. The relationship of the driving force hereinafter to be described, to the shovels is such as to drive them at a great speed whereby the snow is 55 thrown a great distance from the path or walk.

The frame 10 is provided with locomotive means to assist in its movement over the surface of the ground. This means is preferably located centrally between the ends thereof so that the front end of the machine may be raised or lowered with a minimum exertion of force by the operator to bring the scoop and feed wheel into contact with 60 different levels of snow or turned from side

to side in order that the machine may make a wider cut than the mere width of the scoop, and of greater depth than the vertical dimensions of the feed wheel casing. The locomotive means employed in the present 70 embodiment is a pair of wheels 25 and 25^a keyed to a shaft 26 which is journalled in a pair of brackets 27 attached to and depending respectively from each of the side beams 11. The shaft 26 is provided at one end 75 with a sprocket wheel 28 keyed thereto for a purpose which will presently appear. Depending from the side beams in the rear of the wheels are legs 29 preferably formed of straps of iron and which constitute together 80 with the wheels a support for the frame when at rest.

Supported by the frame and preferably located rearwardly of the wheels so as to slightly over balance the shovel, feed wheel 85 etc., is a driving means for the shovel as shown in the form of an internal combustion engine 30, the crank shaft of which is in driving connection with the main shaft 17 on which the shovel wheel and feed wheel 90 are mounted. This connection may be of any well known variety as by means of sprocket wheels 31 and 32 keyed to the shaft 17 and the crank shaft respectively, about which is trained the sprocket chain 33. By 95 the arrangement of the engine 30 so as to slightly over balance the shovel etc., it will be seen that when the machine is at rest, it will be in stable equilibrium supported on the legs and wheels. On the other hand 100 when in operation the pressure and weight of the snow on the front of the machine will counter this overbalance.

It is desirable that a plow of this character should be either adapted to be propelled manually or to be driven by the engine, at the will of the operator. In order that it may be driven by the engine, the shaft 17 is provided with a bevel gear 34, which is keyed thereto and which is in 105 constant mesh with a bevel gear 35, connected to a shaft 36 arranged at right angles to the shaft 17 and journalled upon one of the beams 11 in the journal boxes 37 and 37^a. This shaft extends beyond the frame 110 member and has on its outer end a sprocket wheel 38. A sleeve 39 is secured to the same side of the frame as the journal box 37 and rearwardly thereof in close proximity to the handle 15. Upon this sleeve projecting 115 laterally from the frame and acting as a stub shaft, two sprocket wheels 40 and 41 are mounted for angular and axial movement relative to the sleeve. A sprocket chain is trained about the sprocket wheels 125 38 and 40 whereby the latter is in constant rotation when the engine is running and a sprocket chain 54 is trained about sprocket wheels 38 and 41 whereby when one of these 120 wheels is rotating the other will also rotate.

The sleeve 39 is provided at one end with an enlarged portion 43 affording a shoulder which provides an abutment or thrust bearing for the sprocket wheel 41, and which prevents its detachment from the sleeve at that end. The sprockets 40 and 41 are provided on their adjacent faces respectively with telescoping friction clutch members 52 and 53 held normally out of operative relationship by springs 44 inset into a channel 44^a formed in the face of sprocket wheel 41.

Mounted on the opposite end of the sleeve from that on which the shouldered portion 43 is formed, for sliding movement axially 15 of the sleeve, is a cam block 45 which is prevented from rotary movement by the lug 45^a on the sleeve 39 riding in the groove 45^b formed in the cam block. A cam surface 46 of gradual inclination is formed on the 20 outer face of the cam block for a purpose which will presently appear. Journaled in the bore of the sleeve 39 is a shaft 47 having a finger 48 secured to one end which is adapted to ride over the cam surface 46 25 when the shaft 47 is rotated. The opposite end of this shaft is provided with a handle 49 extending radially therefrom and located in position to be conveniently grasped for operation by the operator.

Pivottally attached at 49^a to the handle 49 is a member 50 which is formed with a series of notches 51 for cooperation with the rod 12 to hold the handle in any position of angular adjustment desired by the operator 35 within a given range.

To facilitate the rotation of sprockets 40 and 41, ball bearings 62 are provided between the sprocket 40 and cam block 45. When the handle 49 is moved downward, 40 the finger 48 will move toward the highest portion of the cam surface 46 and will force the clutch members 52 and 53 into frictional relationship with each other, thereby causing the sprockets 40 and 41 to rotate as a 45 unit and in this manner form a driving connection between the engine and the traction wheels 25. On the other hand, when it is desired to draw the machine backward or when for any other reason it is desired to 50 propel it manually, without the aid of power from the engine, over the ground, the clutch may be released by pressing down the handle 49 and drawing back the member 50, whereupon the sprocket 40 will run idle.

It is desirable to operate the machine hereinbefore described under varying circumstances, as for instance, the plow may be moved forward in a straight line when snow is to be removed from a long and comparatively straight path or roadway, or it may be used on a short sidewalk, or on a long walk having many sharp bends, necessitating frequent turns. In the former case, it is found that the best traction results are obtained by having both wheels rotate with the

axle; in the latter cases, on the other hand, turning is facilitated by having one of the wheels rotate independently of the axle. It is desirable, therefore, that the traction mechanism should be so arranged that either 70 of these results may be obtained at the will of the operator.

In the present embodiment, the said desired results are obtained by having the right wheel and that part of the axle with which 75 it is connected so constructed as to adapt it either to revolve on the shaft 26 or to be keyed thereto, and to rotate therewith as desired by the operator.

The construction of the shaft and wheel 80 by which this result may be accomplished is illustrated in Fig. 8 of the drawings, where-in 25^b designates the hub of the wheel 25; 25^c is a washer between the hub and the axle bearing; and 25^d is a collar keyed to the axle 85 26 by means of a set screw 25^e.

The hub 25^b is provided with a threaded aperture 25^f, and the axle 26 with a corresponding depression 25^g so located as to be adapted to be brought into alignment with 90 the said aperture. A set screw 25^h is screwed into the aperture 25^f, and is adapted to be projected into the depression 25^g to cause the wheel 25 to rotate with the axle 95 or cause the same to be withdrawn from said depression when it is desired to have the wheel revolve independently of the axle.

In order that the shovels 16 and the feed wheel 20, may be prevented from being displaced axially within their respective casings, the portion of the shaft 17 which projects rearwardly of the shovel casing 13 is rotatably mounted in three bearings 17^a, 17^b, and 17^c; the first of which is secured to the casing of the engine 30 and receives the 100 end of the shaft 17 constituting a thrust bearing to prevent rearward displacement. The rear face of the beveled gear 34 keyed to shaft 17 rests against the bearing 17^c, 105 thereby resisting any forward thrust of the shaft. By this arrangement, clogging and 110 injury to the shovel and feed wheel are avoided and the said wheels are maintained in their proper working positions.

In order that the noise from the engine 115 may be silenced to as great an extent as possible and that vibration may be reduced to a minimum, the exhaust pipe 57 is extended downwardly and to one side of the machine so that the discharge opening will lie in close proximity to the snow bank through which the cut is being made. For cooling the engine, a fan 55 is provided suitably mounted on the frame and driven in any convenient manner, as by a belt 56 120 trained about pulleys 58 and 59 keyed respectively to the main shaft 17 and the fan shaft 60. A suitable gas control 61 may be provided and located as shown for convenient manipulation by the operator, as 125 130

shown, located on the opposite side of the machine from the handle 49, thereby distributing the operating movement between the two hands of the operator. The machine is provided with the usual fuel tank 621, conveniently mounted on the frame for feeding the fuel by gravity to the engine cylinders.

It will appear from the foregoing description that I have produced a machine for cleaning snow off of walks or roadways which is simple in construction; simple of operation; with the parts so arranged as to be convenient for operation with a minimum of exertion on the part of the operator; that this machine by its construction is adapted for operation upon straight roadways or walks or upon paths which are irregular or winding in their courses and which have sharp turns; and may be simply and easily manipulated to cut a path of greater width and depth than the width and depth of the shovel of the machine; that it may be propelled manually or by motive power at the will of the operator; and which operates with but slight noise and vibration.

Having fully described my invention, what I claim is:—

1. A snow plow comprising a frame, a shovel at one end of the frame and handles formed at the opposite end, wheels supporting the shovel in spaced relation to the ground when the frame is in horizontal position, said wheels being located substantially midway between the shovel and handles.
2. A snow plow comprising a frame, wheels supporting said frame in spaced relation to the ground, a shovel at the forward end of the frame, and handles at the rear end for manipulating the shovel to various levels of snow and for guiding the plow.
3. In a device of the character described, a frame, traction wheels located approximately midway of the ends of said frame, guiding handles at the rear end of the frame, a rotary shovel at the forward end of said frame, motive means on said frame for rotating said shovel, and means for making and breaking a driving connection between the motive means and said traction wheels.
4. In a snow plow, a frame, a power-driven shovel at one end of the frame, handles at the opposite end of the frame, wheels located intermediate the ends of the frame and supporting the frame and shovel in spaced relation to the ground when the frame is in a horizontal position.
5. In a device of the character described, a frame, wheels mounted intermediate the ends of said frame for affording locomotion to said frame, said frame being connected with the wheels so as to lie above the same when in a horizontal position, handles at one end of the frame, a rotary shovel at the opposite end of the frame, and means

supplying driving power to said rotary shovel.

6. A snow plow comprising a frame having a rotary shovel at one end and handles at the opposite end, wheels secured to said frame between the shovel and handles, the relation of the frame to the wheels being such that when the frame rests in a horizontal position the shovel will be spaced from the ground a distance greater than the length of the radius of the shovel.

7. A snow plow of the character described comprising a frame, a rotary shovel at the forward end of said frame, an internal combustion engine on said frame, an exhaust pipe leading from said engine downward to a position near the ground when the machine is at rest, said pipe being curved to one side toward its lower end.

8. In a machine of the character described, means for cleaning snow or the like from a sidewalk, path, or roadway, traction means for said machine comprising a shaft, a pair of traction wheels on said shaft, one of which is permanently keyed to the shaft for rotation therewith, the other being adapted to be keyed to the shaft for rotation therewith or to revolve thereon and independently thereof at the will of the operator.

9. In a machine of the character described, a frame having handles formed at one end, a rotary shovel mounted in a casing secured to the other end of said frame, power means on said frame for operating said shovel, and traction means supporting said frame and attached thereto between said handles and said casing, means to connect said wheels in driven relation to said power means or disconnect it therefrom at the will of the operator, said handles being located in the rear of the traction means a distance approximately equal to the forward end of the casing from the wheels, and said casing being supported in spaced relation to the ground a distance greater than the length of the radius of the shovel when the frame is in a horizontal position.

10. In a snow plow, a frame having a shovel at one end and handles at the other end, the total length of the machine being only slightly in excess of twice the greatest width of the machine.

11. In a snow plow a frame, a shovel at one end and handles at the opposite end, the total length of the machine being less than three times the greatest width of the machine.

12. A snow plow having locomotive means, a frame mounted on said locomotive means having a shovel at one end and handles at the opposite end, said handles being located rearwardly of said locomotive means a distance not greater than that from the forward end of said shovel to said locomotive means.

13. A snow plow, comprising a frame

mounted on wheels and having a shovel at one end and handles at the opposite end, the length of said frame being less than three times its width, and being so mounted on said wheels that when the machine is in its normal position of rest the shovel will be in spaced relation to the ground.

14. A snow plow comprising a frame

mounted on wheels and having a shovel at one end and handles rigidly connected to the other end, said wheels being located substantially midway between the ends of the frame and the length of the machine being less than three times its greatest width.

In testimony whereof I affix my signature.
RICHARD T. CHILES.
